Ade Bethune, Newport, R.I., assignor to Terra-Sancta Creations, Inc., Philadelphia, Pa.

Original design application Apr. 8, 1970, Ser. No. 22,320, now Patent No. 221,054, dated July 6, 1971. Divided and this application Oct. 30, 1970, Ser. No. 25,733

Term of patent 14 years

Int. Cl. D8—09

U.S. Cl. D8—177

FIG. 1 is a front perspective view of a door knocker showing my new design;

FIG. 2 is a front elevational view thereof;

FIG. 3 is a side elevational view thereof showing the side opposite to that shown in FIG. 1;

FIG. 4 is a bottom plan view thereof; and

FIG. 5 is a back elevational view thereof.

While the letters on the front of the door knocker have been shown in specific colors, it will be understood that the colors thereof may vary, or be omitted entirely, without departing from the scope of this invention.

This is a division of design application Ser. No. 22,320 filed Apr. 8, 1970 and now patented No. D. 221,054, granted July 6, 1971.

I claim:

The ornamental design for a door knocker, as shown and described.
